BOX LIDDER FEED

Hale Paxton, Santa Ana, Calif., assignor to Food Machinery Corporation, San Jose, Calif., a corporation of Delaware

Original application April 24, 1935, Serial No. 17,970. Divided and this application February 21, 1938, Serial No. 191,585

7 Claims. (Cl. 1—10)

This invention relates to devices for feeding boxes to and from a lidder and has particular utility in the operation of a lidder in lidding boxes overfilled with fresh fruits or vegetables.

5 This case is a division carved from the joint application Ser. No. 17,970, filed April 24, 1935, by Chester E. O'Donnell and myself on a "Method of and apparatus for packing fresh whole fruits and the like".

10 The present invention embraces that portion of the subject matter presented in the parent case above referred to which relates to the feeding of a packed box into a lidder and the coordinate ejecting of the lidded box from said lidder.

15 It is an object of my invention to provide an improved mechanism for automatically feeding packed boxes to a lidder and removing the lidded boxes therefrom.

The manner of accomplishing this object as 20 well as further objects and advantages will be made manifest in the following description taken in connection with the accompanying drawings:

Figure 1 is a front elevational view of the preferred embodiment of the invention.

25 Fig. 2 is a horizontal sectional view taken on the line 2—2 of Fig. 1.

Fig. 3 is an enlarged fragmentary perspective view illustrating the details of the control mechanism in the pre-presser.

30 Fig. 4 is a fragmentary sectional view taken on the line 4—4 of Fig. 2.

Fig. 4a is a fragmentary diagrammatic view, taken on the direction of the arrow 4a of Fig. 3, and illustrating the overthrow mechanism of the pre-presser in neutral position.

35 Fig. 4b is a view similar to Fig. 4a and illustrates the overthrow mechanism in position for elevating the press table.

Fig. 4c is a view similar to Fig. 4b and illustrates the overthrow mechanism in position for 40 lowering the press table.

Fig. 5 is a fragmentary operation view of the pre-presser and control mechanism for feeding the box into the lidder and shows the pre-presser table moving downwardly with the ejector dog shifting the box against the discharge stop to position the latter over the operating cam therefor.

Fig. 6 is a fragmentary operation view illustrating the situation at the instant of completing 50 the downward movement of the pre-presser table in progress in Fig. 5.

Fig. 7 is a transverse sectional view taken on the line 7—7 of Fig. 6.

55 Fig. 7a is an enlarged transverse sectional view

similar to Fig. 7 and showing the box stop in elevated position.

Fig. 8 is a view similar to Fig. 5 and illustrating the ejection of a box from the pre-presser into the lidder with the consequent restoration of the discharge stop in the pre-presser to its vertical position, and the automatic lowering of the stop operating cam into its inoperative position.

Fig. 9 is a view similar to Fig. 5 illustrating the situation where the table of the pre-presser has arrived downwardly with a loaded box during the performance of a lidding operation in the lidder, this view showing the lidder table returning to its downwardmost position, upon arrival at which this table will shift the pre-presser discharge stop operating cam against a roller on such stop to disengage this stop from the box on the pre-presser table.

Fig. 10 is an enlarged fragmentary sectional detail view taken on line 10—10 of Fig. 6 and showing the stop cam operating latch and lug.

Referring specifically to the drawings the apparatus of my invention illustrated therein may be indicated by the numeral 20, this apparatus including a lid pressing, nailing and strapping machine 21, a pre-pressing machine 22, and a box conveyor and feed mechanism 23 for supplying overfilled packed boxes with the machine 21 and 22.

The lid pressing, nailing and strapping machine 21 is preferably similar in structure and operation to the machine of this type disclosed in application Ser. No. 688,104, filed September 5, 1933, by myself and joint inventors Gerald C. Paxton and Harry D. Benson, or it may be like the machine disclosed in application for U. S. Letters Patent Ser. No. 709,176, filed January 31, 1934, by the same three applicants, said applications having been co-pending with the parent case of the present divisional application, and having since 35 issued as U. S. Letters Patent No. 2,084,048 and No. 2,093,733, respectively.

Neither side flushers nor a crown sheet are employed in the machine 21. With this exception and the exceptions to be noted hereinafter, the machine 21 may be identical with the machine described in either of the co-pending applications.

The machine 21 has a frame 32 and a nailing table 33 vertically reciprocable within the frame 32 by a power unit 34 controlled by a pedal 35. 50 Mounted on the upper end of the frame 32 are nailing heads 36 and a strapper head 37.

The nailing table 33, a plan view of which is shown in Fig. 2, includes end cross bars 40 having upright guide bars 41 at their opposite ends 55

for sliding within vertical angle iron members 43 of the frame 32. The end bars 40 are connected by longitudinal bars 44 and 45 upon which are mounted idle rollers 46. Pivots 5 mounted on the cross bars 40 and having operating mechanism exactly as shown in the first mentioned co-pending application are side flusher shafts 48, the shaft carrying no flushers, however, but instead lateral box centralizers 49 and longitudinal box centralizers 50 which brought into operative relation with a box on the table 33 when the table is elevated by inward swinging of shafts 48, as fully described in the first above mentioned co-pending application.

15 Mounted between the bars 45 is a box ejector and stop mechanism 52. The mechanism 52 includes a discharge stop 57 and a rebound box stop 58. Connecting the stop 57 with a downward extending arm 53 on one of the shafts 48 is 20 a link 54 which swings the stop 57 down away from in front of a box on the table 33 each time the shafts 48 are swung inwardly by the lifting of the table. The link 54 is telescopic in construction and includes a rod 54a which has a 25 head 54b at one end and a clevis 54c at the opposite end which pivotally connects to the arm 53. The rod 54a is slideable in lugs 54d provided on a member 54e which is pivotally connected to an arm 57a extending laterally from the hub of 30 the stop 57. Coiled about the rod 54a between the clevis 54c and the lowest of the lugs 54d is an expansive spring 54f which tends to maintain the link 54 in its extended condition of greatest length as shown in Fig. 4 but which 35 permits the telescoping of this link to reduce its length.

The stops 57 and 58 (Figs. 1, 2, 9 and 10) are mounted on a shaft 52a, the opposite ends of which are supported on the table bars 40. The 40 stop 57 is rotatable on this shaft and is yieldably urged against a collar 52b, fixed on the shaft, by a short expansion spring 52c coiled about the shaft. When a box is delivered onto the table 33, it depresses the stop 58 which is 45 pivotally mounted on a block 58a fixed on the shaft 52a, the stop 58 (Fig. 10) being yieldably pressed upwardly into its stop position as shown in Fig. 1. When this box hits the stop 57, it compresses the spring 52c, the box at this time 50 clearing the stop 58 and permitting the latter to be lifted by its hidden spring into its stop position as shown in Fig. 1. When the inertia of the box has been stopped by the compression of the spring 52c, this spring shifts the box 55 backwardly against the stop 58, there still being a gap between stop 57 and the collar 52b when this takes place. Upon the operation of the lidding machine 21, as described in the first aforementioned co-pending application, the inward swinging of the shafts 48 by engagement of rolls 48a with cam tracks 48b shown in Fig. 4, causes the stop 57 to be rotated by the link 54 until the stop is disposed downwardly from in front of the box. The pressure of the spring 52c against the stop 57 immediately forces this 60 along the shaft 52a against the collar 52b so that the stop 57 is now disposed under the box. With the downward movement of the table 33, the shafts 48 are returned to their positions as 65 shown in Fig. 4 by springs 53a connecting the lower ends of arms 53 on the shafts 48. Normally the box is still disposed over the stop 57 when the table 33 reaches its downwardmost position as shown in Fig. 4, so that the stop 70 75 57 cannot be returned to its upward position by

the link 54. This being the case, the link 54 telescopes as above described causing the compression of the spring 54f and when the box has entirely passed over the stop 57, this spring extends the link 54 to its full length and returns the stop 57 to its upwardmost position as shown in Fig. 4.

The ejector and stop mechanism 52 also includes an ejector spring 52d, coiled about the shaft 52a and anchored at its forward end adjacent the collar 52b. The opposite end of the spring 52d connects to a block 52e slideable on the shaft 52a and carrying an ejector dog 52f which is constantly spring pressed into its upwardmost position as shown in Fig. 1. Pivots 10 mounted on the block 58a is a chain pulley 58b over which a chain 58c, connected to the block 52e, extends, this chain passing downwardly as shown in Fig. 5 and connects to a spring means 58d mounted on the frame 32 of the lidder 21. The spring 20 means 58d takes up the slack in the chain 58c when the table 33 is in its downwardmost position and as the table rises with the box disposed between the stops 57 and 58, the chain 58c compresses the spring 58d to its limit and 25 then pulls the block 52e with the ejector dog 52f thereon in a leftward direction until this dog is free to be spring pressed upwardly opposite the rear end of the box as shown in Fig. 9. Thus, when the box is freed from the longitudinal centralizers 50 and from the stop 57 by the outward swinging of the shafts 48, the power of the spring 52d is released against the box through the ejector dog 52f in ejecting the box from the lidder 21, this returning the dog 52f and spring 35 52d to the condition in which these are shown in Fig. 2.

Pivots 40 mounted on the inner face of a downward extension from the front one of the longitudinal bars 45 as shown in Figs. 1 and 2, is a 40 spring pressed latch 55 having a lug 56 (Fig. 10) extending inward therefrom, this latch being positioned to be engaged by a box entering the machine 21, rocked about its axis and then disengaged by said box before the latter comes to 45 rest upon the table 33 in its proper position. Leading from the discharge end of the machine 21 is a section of roller conveyor 59.

The pre-presser 22 has a frame 62, a vertically reciprocable table 63 and a table elevating power 50 unit 64, all of which are identical with the corresponding parts of the lid nailer and strapping machine 21 with the exceptions to be noted hereinafter.

Mounted upon upper ends of four angle iron 55 corner posts 65 of the frame 62 is a presser plate assembly 66 including longitudinal bars 67 and 68 upon which are yieldably mounted a compressor plate 74, which is formed in two halves each of which is supplied with a soft rubber 60 pad 79.

As above stated, the table 63 is supported on and vertically reciprocable by the power unit 64 in the same manner as described in the first above mentioned co-pending application. As 65 shown in Fig. 2, the table 63 is substantially similar to the table 33 of the machine 21, and both of the tables in their downwardmost positions are on the same level. Parts of the table 63, like corresponding parts of the table 33, are as 70 follows: end bars 95 having upwardly extending guide arms 96 and connected by longitudinal bars 97 and 98, between which are mounted rollers 99, there being an ejector and stop assembly 100 mounted between the bars 98 which is sub- 75

stantially like the assembly 52 excepting as to the means of operating the discharge stop 101.

The ejector and stop assembly 100 (Fig. 3) includes a shaft 105 which is supported as by 5 having its opposite ends welded upon the end bars 95 of the table. This shaft supports a block 106 fixed thereto, said block carrying a chain pulley 107, underneath the bar 105, and a box rebound stop 108 pivotally mounted on 10 said block and yieldably spring pressed upwardly into the position in which it is shown in Fig. 3. Fixed upon the shaft 105 adjacent the opposite end of the table 63 is a spring anchor collar 110 to which is anchored a heavy contractile spring 15 111 which is coiled about the shaft 105. The opposite end of this spring is connected to a slide block 112 on which is pivotally mounted an ejector dog 113, this being yieldably urged upwardly into the position in which it is shown in 20 Fig. 3 by a small concealed spring on said slide block.

The frame 62 (Fig. 3) includes a longitudinally disposed channel iron member 115 and a flexible chain 116 extends from the slide block 112, 25 over the pulley 107, and downwardly through a suitable aperture in the member 115 where it is yieldably held by a spring means 117 (Fig. 1).

Extending downwardly from one of the longitudinal bars 97 as shown in Fig. 8 is a spring 30 bracket finger 124. As shown in Fig. 3, the discharge stop 101 has a hub 126 which, with a strong, stiff compression spring 127 is trapped on the shaft 105 between the adjacent end bar 95 and a stop collar 128. As shown in Fig. 7a, the 35 hub 126 has a downwardly extending bearing arm 129 which is apertured to receive a stub shaft 130 on which a cam roller 131 is rotatably mounted. The bearing arm 129 has a lateral extension 132 which is connected by a contractile 40 spring 133 to the spring bracket arm 124. The spring 133 yieldably maintains the discharge stop 101 in upright position as shown in Figs. 1, 2, 3, 5, 7a, 8 and 9.

As shown in Figs. 1 and 2, the machines 21 45 and 22 are connected by a short idle roller conveyor section 145, the opposite ends of which are secured to the frame 32 and 62 of these machines respectively. Provided on the conveyor section 145 are bearing blocks 147 which carry a shaft 50 148 having mounted thereon a cam supporting rocker 149. The rocker 149 has arms 150 which slidably support a cam 151 as shown in Figs. 1, 2, 5, 6, 8 and 9. Light coil springs 152 on the arms 150 maintain the cam 151 against cap 55 screws 150a screwed into the ends of arms 150. The rocker 149 also has an arm 153 which extends upwardly within the structure of the table 33 when this is in its lowermost position and is engaged by a horizontal surface on the latch 55 60 whenever the latter moves downwardly with the table 33 into its lowermost position as shown in Fig. 1. Whenever the arm 153 is disengaged by the latch 55, the rocker 149 rocks by gravity owing to the weight of cam 151 so as to lower 65 the latter into its lowermost position in which it is shown in dotted lines in Fig. 7a.

The table 63 has flusher shafts 160 which are actuated in identically the same manner as illustrated in the first of the aforementioned co-pending applications, that is by rollers 161 and cam tracks 162 (see Fig. 4). These shafts have upwardly extending arms 163 carrying lateral box centralizing members 164, longitudinal box centralizing members 165 and side flusher 75 blades 166.

Pivottally mounted on opposite ends of each flusher 166 is an end flusher 168 having an operating arm 169 which is connected by a link 170 to a goose neck 171 formed on the upper end of the adjacent table guide member 96. When the 5 table 63 is elevated and the rollers 161 strike the cams 162, the shafts 160 are rotated, swinging the flushers 166 inwardly. The goose necks 171, of course, move upwardly with the table 63 and, with the inward movement of the flushers 166, 10 the end flushers 168 are swung into end flushing positions as shown in Fig. 6 by the links 170, the end flushers reaching these positions just as the side flushers 166 reach their full inward flushing 15 positions shown in this figure.

The table 63 also carries an apertured upward limit control finger 175 (Figs. 1 and 3) and a downward limit control cam 176. Carried on the inner face of one of the longitudinal bars 98 of the table 63 is a low voltage box delivery control 20 switch 177 (Figs. 1 and 3) having a switch finger 178.

Extending forwardly from the channel frame member 115 (Fig. 3) is a frame bracket 180, and a switch control shaft 181 is pivotally mounted 25 between this bracket and a member 182 of the frame 62. The control arm 181 has arms 185, 186, 187, 188 and 189 provided thereon. The arm 185 is connected by a link 190 (Fig. 1) to an eye 191 which surrounds the stem 192 of a switch 193 30 which controls the power elevating mechanism 64 and which is constructed and operates in exactly the same manner as the corresponding switch in the first above mentioned co-pending application. The stem 192 has collars 194 and 35 195 which are disposed above and below the eye 191.

The arm 186 connects to the lower end of a control rod 196 (Fig. 1) which extends upward through the aperture in the finger 175 and has 40 its upper extremity guided vertically by a guide 197 provided on the overhead frame plate 67 as shown in Fig. 1. The rod 196 has an upward limit collar 198 provided thereon as shown in Fig. 1, the position of this collar on the rod 196 45 being adjustable, and being adapted to be engaged by the upward limit finger 175 on the table 63 as this table approaches its upwardmost position to reverse the switch 193 and the operation of the elevator mechanism 64, this causing the 50 table to be lowered.

The arm 187 as shown in Figs. 1 and 3 is adapted to be engaged by the downward limit control cam 176 on the table 63 as the latter approaches its downwardmost position so as to rock 55 the shaft 181 and operate the switch 193 to halt the downward movement of the table 63. The arm 188 is connected through a link 200 with a full bell crank 201 which is in turn connected by a link 202 to a lever 203 pivotally mounted on 60 a bracket 204 which is supported on the channel member 115. The upper end of the lever 203 has a dog 205 pivotally mounted thereon as shown in Fig. 3, this dog being yieldably held by a spring 206 in the position shown. The arm 189 has a 65 pin 210 at its lower end which is connected by a contractile spring 211 to a pin 212 provided on the bracket 180. Also provided on this bracket are stops 213 and 214.

The box conveying and feed mechanism 23 is 70 best shown in Figs. 1 and 2 and includes a horizontal belt conveyor system for collecting the packed boxes to be handled in the apparatus 20, this system being represented by the conveyor 220 and being driven by a motor 221 connected to 75

this conveyor. This motor is controlled by switches 222 and 223 having arms 224 and 225 which are positioned as shown in Figs. 1 and 2 so as to be engaged by boxes travelling upon the conveyor 220 and upon a short section of idle conveyor 227 located between the conveyor 220 and the machine 22. The motor 221 is driven by power transmitted through switches 222 and 223 with the latter connected in parallel so that this motor runs continuously excepting when both arms 224 and 225 are engaged by boxes as aforesaid to deenergize the motor 221.

Mounted so as to extend slightly above the uppermost surface of the idle roll conveyor section 227 just at the entrance to the machine 22 is a feed roller 230 which is power driven by a motor 231, current being supplied to said motor through the switch 177, the motor being deenergized whenever the arm 178 is depressed by a box resting on the table 63. Owing to the necessity for the table 63 to reciprocate vertically in the operation of the machine 22, switch 177 is, of course, connected to the motor 231 through a flexible cord.

Operation

The operation of the apparatus 20 is as follows. Electricity is first supplied to the various switches for running the motors controlled thereby. Assuming the machines 21 and 22 and the conveyors 220 and 227 to be empty, the conveyor 220 is thus set in motion by the motor 221 and the feed roller 230 is rotated by its motor 231. As boxes B travel along the conveyor 220 onto the idle roll conveyor section 227 so as to extend onto the feed roller 230, this feed roller picks up the foremost box and delivers it at an accelerated speed onto the table 63 of the machine 22. The rapidity of this delivery causes the box, upon engaging the discharge stop 101 to compress the spring 127 measurably as shown in dotted lines in Fig. 9, and as the inertia of the box is overcome, the latter is repelled back against the stop 108 which in the meantime has been lifted by its spring into position at the rear of the box. With this rearward movement, the box also engages the dog 205 and shifts this rearwardly thereby rocking the lever 203 to swing the lower end of this forwardly and, through the linkage 200, 201 and 202 and the arm 188, rocking the shaft 181 to swing the overthrow arm 189 from the position in which it is shown in Figs. 3 and 4a to the position in which the latter arm is shown in Fig. 4b. It will be noted that in this movement of the arm 189 the axis of spring 211 is shifted across the axis of the shaft 181 to bring the arm 189 against stop 213 so that the spring 211 now retains the shaft 181 in the position into which it was just shifted. This rotation of the shaft 181 lifts upon the link 190 and the eye 191 (see Fig. 1) so as to lift on the collar 194 carried by the link 190 thereby drawing upwardly the stem 192 of the switch 193. This actuates the switch to set in motion the elevator mechanism 64 thereby starting to move the elevator table 63 upwardly. Owing to the fact that the spring 211 holds the arm 189 in the position in which it is shown in Fig. 4b this upward movement of the table 63 will now continue until some positive force has been applied to throw out the switch 193.

As box B moves onto the table 63 and over the switch 177, it engages the switch arm 178 and shuts off the motor 231, thus stopping rotation of the feed roller 230. Any box delivered onto the conveyor section 227 therefor while the box B is still resting on the table 63 will merely come to

rest with its forward end resting on the roller 230 as box B is shown in Fig. 1. When resting in this manner, the foremost box has moved entirely off the conveyor 220 so as not to interfere with continued operation of the latter. When in this position, the foremost box engages the arm 225 and swings it so as to shut off the switch 223. If, while this box remains in this position, another box arrives at the discharge end of the conveyor 220 so as to engage and swing the arm 224 and shut off the switch 222, this deenergizes the motor 221 and causes the conveyor system terminating with the conveyor 220 to be halted. This halting of the conveyor 220 continues until the foremost box is subsequently delivered into the machine 22, as will be described hereinafter.

As the table 63 is elevated with the box B resting thereupon, the fruit F which extends above the upper end of the box is brought into engagement with the pad 90 of the pressing plate 74 so as to compress this fruit into the box and leave the upper face of this fruit disposed with an arcuate contour corresponding to that of the presser plate 74. The amount of pressure thus applied is determined by the position of the collar 198 on the control rod 196 so as to select the height at which the table has been lifted before the switch 193 is reversed thus causing the elevator mechanism 64 to cease elevating the table 63 and commence drawing the latter back down- wardly.

A center guard 80 disposed over a partition P of the box B comes to rest on this partition and is lifted upwardly thereby during the elevation of the box.

As the table 63 rises, spring means 117 as shown in Fig. 1 is first compressed and then draws downwardly on the chain 116 to draw the slide block 112 leftward and stretch spring 111. This carries the ejector dog 113 to the left until it comes up underneath the reversal stop 108 opposite the rear end of the box B. As the elevator table starts downwardly, the dog 113 is shifted by the springs 111 against the rear end face of the box B and further contraction of the spring 111 for the time being is now prevented by the trapping of the box between the centralizers 165 and the presence of stop 101 along the path in which the box must be ejected in feeding this into the ladder 21. When the table 63 has moved downwardly to the point illustrated in Fig. 5, the centralizers 164—165 and flushers 167—168 have been withdrawn from their embrace of the box.

With this release of the box B from all restraint but that of the stop 101, the powerful pressure exerted against the box by the spring 111 compresses the weaker spring 127 between the discharge stop 101 and the adjacent end bar 95 of the table 63, this movement of the box taking place a short distance before the table 63 reaches its lowermost position. This shifting of the discharge stop 101 along the shaft 105 shifts the roller 131 longitudinally to position it above the cam 151 with the result that as the table 63 completes its downward movement, the roller 131 engages the cam 151 on its cam surface 151a which rocks the discharge stop 101 about the shaft 105, this resulting in the release of the box B, as shown in Fig. 6, followed by the ejection therefrom by the ejector 100, so as to impel this box over the idle conveyor 145 and into the machine 21 as shown in Fig. 8.

As the box enters the machine 21, it engages latch 55 and swings it forwardly thus shifting the lug 56 on the latch 55 (Fig. 10) away from over

the arm 153 of the cam rocker 149. This engagement permits the weight of the cam 151 (Fig. 8) to rock the rocker 149 to lower the cam 151 out of operative relation to the roller 131 on the stop 101. However, at the very instant the stop 101 is rotated downwardly away from in front of the box B, as shown in Fig. 6, the spring 127 expands to push the stop 101 inwardly into contact with the collar 128. Thus, when the box B has passed over the stop 101, the roller 131 on said stop is not only rendered free from cam 151 by the lowering of the latter as aforesaid, but is also now out of alignment with this cam by the response above noted of the stop 101 to the spring 127. The stop 101 is thus doubly free to respond to its normalizing spring 133 which returns the stop to its upright position as shown in Fig. 8.

From the foregoing, it is clear that the delivery of a box onto the table 33 in the lidder 21 disengages the latch 55 from the cam rocker arm 153 so as to permit the cam 151 to drop into its inoperative position relative to the stop 101. It is likewise clear that the cam 151 must be raised into operative position before a box may again be discharged from the pre-presser 22. The only way in which the cam 151 can be thus raised is by the elevation of the table 33 of the lidding machine 21 a sufficient distance so that on its return downward the lug 56 on the latch 55 will engage 30 and rock the cam rocker 149 to lift the cam 151.

A reciprocation of the table 33 having this effect may be accomplished by manipulating the pedal 35, of course, without lidding a box resting on this table. However, in the normal operation of the apparatus 20, no such partial reciprocation of the table 33 would take place. Instead, each time a box is delivered to the machine 21 and is centralized longitudinally by the stops 57 and 58, the operator, after placing a lid L in the machine and inserting a strap in the strapper head 37, steps on the pedal 35 causing the elevating mechanism 34 to lift the table 33 against the nailing heads 36 and the strapper head 37 so as to apply a lid to the box with the ends of the lid engaging the ends 45 of the box, nail the lid ends to the box ends, place the strap over the middle of the cover, and secure the ends of the strap to the sides of the box. When this is accomplished, the operator releases his foot from the pedal 35 which automatically 50 results in the reversal of the motor in the elevating mechanism 34 thereby withdrawing the table 33 downward to its lowermost position as shown in Fig. 1. The stop 57 is rotated out of stop position with the downward movement of the table 33 by suitable linkage connecting this stop to the flusher shafts 48, and the longitudinal box centralizers 58 are also withdrawn by the rotation of such shafts to nonimpeding positions as shown in this figure, whereupon the ejector dog of the mechanism 52 ejects the lidded and strapped box 55 from the table 33 onto the gravity conveyor section 59.

Whenever a complete reciprocation of the table 33 takes place in lidding a box, a return of the table to its downwardmost position as shown in Fig. 1 always results in the lug 56 on the latch 55 engaging the cam rocker 149, this lifting the cam 151 into operative position. When this occurs, of course, a lidded box is just being ejected from the table 33, leaving the latter ready to receive another box to be lidded. If, when the table 33 thus moves downwardly, the table 63 of the pre-presser 22 is in its downwardmost position with a box resting thereon and waiting to be ejected therefrom, the upward movement of the cam 151

resulting from the return of the table 33 to its lowermost position will cause the cam 151 to engage the roller 131 and rotate the stop 101 out from in front of the box B on the table 63 in exactly the same manner as, and with the same results as above described, where the cam 151 was latched in raised position and was then engaged by the roller 131 as the table 63 returned to its lowermost position. That is, in either case, the cam 151 rotates the stop 101 out from in front of the box on the table 63 allowing the box to be ejected by the ejector 100, discharging the box rapidly from the machine 22 into the machine 21.

What I claim is:

1. In combination: a lidder including a nailing 15 table, lid pressing and nailing mechanism suspended overhead, and an elevator for lifting said table with a packed box resting thereon into operative relation with said mechanism to lid said box, and then lowering said table to permit the 20 lidded box to be discharged therefrom; feeding means for delivering a box onto said table; stop means for preventing a box from passing from said feeding means into said lidder; and control means responsive to the downward travel of said 25 table to render said stop means inoperative to stop said last mentioned box from being fed into said lidder.

2. In combination: a lidder including a nailing 30 table, lid pressing and nailing mechanism suspended overhead, and an elevator for lifting said table with a packed box resting thereon into operative relation with said mechanism to lid said box, and then lowering said table to permit the 35 lidded box to be discharged therefrom; feeding means for delivering a box onto said table; stop means for preventing a box from passing from said feeding means into said lidder; control means responsive to the downward travel of said 40 table to render said stop means inoperative to stop said last mentioned box from being fed into said lidder; and means automatically restoring said stop means to box stopping condition with the passage of a box thereover.

3. In combination: a lidder including a nailing 45 table, lid pressing and nailing mechanism suspended overhead, and an elevator for lifting said table with a packed box resting thereon into operative relation with said mechanism to lid said box, and then lowering said table to permit 50 the lidded box to be discharged therefrom; feeding means for delivering a box onto said table; stop means for preventing a box from passing from said feeding means into said lidder; control means responsive to the downward travel of said 55 table to render said stop means inoperative to stop said last mentioned box from being fed into said lidder; and means freeing said stop means from said control means to permit said stop means to stop another box subsequently arriving 60 adjacent thereto.

4. In combination: a lidder including a nailing table, lid pressing and nailing mechanism suspended overhead and an elevator for lifting said table with a packed box resting thereon into 65 operative relation with said mechanism to lid said box, and then lowering said table to permit the lidded box to be discharged therefrom; feeding means for rapidly propelling a box onto said table; stop means for preventing a box from 70 passing from said feeding means into said lidder; and control means responsive to the downward travel of said table to render said stop means inoperative to stop said last mentioned box from 75 being fed into said lidder.

5. In combination: a lidder including a nailing table, lid pressing and nailing mechanism suspended overhead and an elevator for lifting said table with a packed box resting thereon into operative relation with said mechanism to lid said box, and then lowering said table to permit the lidded box to be discharged therefrom; feeding means for rapidly propelling a box onto said table; stop means for preventing a box from passing from said feeding means into said lidder; control means responsive to the downward travel of said table to render said stop means inoperative to stop said last mentioned box from being fed into said lidder; and means automatically 10 restoring said stop means to box stopping condition with the passage of a box thereover.
6. In combination: a lidder including a nailing table, lid pressing and nailing mechanism suspended overhead, and an elevator for lifting said table with a packed box resting thereon into operative relation with said mechanism to lid said box, and then lowering said table to permit the lidded box to be discharged therefrom; feeding means for delivering a box onto said table; stop means for preventing a box from passing from said feeding means into said lidder; con- 20
- 25

trol means responsive to the downward travel of said table to render said stop means inoperative to stop said last mentioned box from being fed into said lidder; and means independent of the box entering said lidder to be lidded, for automatically removing the previously lidded box from said lidder. 5

7. In combination: a lidder including a nailing table, lid pressing and nailing mechanism suspended overhead, and an elevator for lifting said table with a packed box resting thereon into operative relation with said mechanism to lid said box, and then lowering said table to permit the lidded box to be discharged therefrom; feeding means for delivering a box onto said table; stop means for preventing a box from passing from said feeding means into said lidder; control means responsive to the downward travel of said table to render said stop means inoperative to stop said last mentioned box from being fed into said lidder; and means independent of the box entering said lidder to be lidded, for automatically and rapidly ejecting the previously lidded box from said lidder. 15 20

HALE PAXTON. 25
